FOREIGN PATENT DOCUMENTS

JP 1120446 9/2001 .... 14/3

Primary Examiner—Jeffrey Asch

(74) Attorney, Agent, or Firm—Greenberg Traurig, LLP; Charles Berman, Esq.; Donald Wenskay, Esq.

CLAIM

The ornamental design for a surface configuration of a two-way radio front, as shown and described.

DESCRIPTION

FIG. 1 is a front view of a surface configuration of a two-way radio front; and,

FIG. 2 is a front view of a second embodiment of the surface configuration of the two-way radio shown in FIG. 1. The broken line showings are for illustrative purposes only and form no part of the claimed design.

The broken lines throughout the views, showing surface shading meant to indicate three-dimensionality, are for illustrative purposes only and form no part of the claimed design.
